[57] CLAIM

The ornamental design for a decorative bed frame, as shown and described.

DESCRIPTION

FIG. 1 is a perspective view of a design for a decorative bed frame.

FIG. 2 is a front elevational view of the decorative bed frame.

FIG. 3 is a right side elevational view of the decorative bed frame.

FIG. 4 is a top plan view of the decorative bed frame.

FIG. 5 is a rear elevational view of the decorative bed frame.

FIG. 6 is a front elevational view showing in greater detail the left front leg of the decorative bed frame, the right front leg being a mirror image of the left front leg, wherein this view is only shown for convenience of illustration, and this view is not intended to show a distinct design separate from the decorative bed frame.

FIG. 7 is a perspective view showing in greater detail the rear, left side side and a portion of top of the left front leg of the decorative bed frame, wherein this view is only shown for convenience of illustration, and this view is not intended to show a distinct design separate from the decorative bed frame.

FIG. 8 is a perspective view showing in greater detail portions of the front rail and the left side rail, as well as the front, right side and a portion of the rear of the left front leg of the decorative bed frame, wherein this view is only shown for convenience of illustration, and this view is not intended to show a distinct design separate from the decorative bed frame.

FIG. 9 is a perspective view showing in greater detail the left side, front and a portion of top of the left front leg of the decorative bed frame, wherein this view is only shown for convenience of illustration, and this view is not intended to show a distinct design separate from the decorative bed frame.

FIG. 10 is a top plan view showing in greater detail the left front leg of the decorative bed frame, wherein this view is only shown for convenience of illustration, and this view is not intended to show a distinct design separate from the decorative bed frame; and,

FIG. 11 is a perspective view showing in greater detail the rear of the left front leg of the decorative bed frame, wherein this view is only shown for convenience of illustration, and this view is not intended to show distinct design separate from the decorative bed frame.
